UNITED STATES PATENT OFFICE.

GEORGE I. SLATER, OF FREDONIA, ASSIGNOR OF THREE-FOURTHS HIS
RIGHT TO R. A. HARSH AND J. N. DUNHAM, OF SAME PLACE, AND
E. G. EBERMAN, OF MERCER, PENNSYLVANIA.

IMPROVEMENT IN MOTIVE POWERS.

Specification forming part of Letters Patent No. 154,919, dated September 8, 1874; application filed
August 26, 1874.

To all whom it may concern:

Be it known that I, GEORGE I. SLATER, of Fredonia, in the county of Mercer and State of Pennsylvania, have invented certain new and useful Improvements in Motive Power, of which the following is a specification:

My invention relates to certain new and useful improvements in apparatus or motors for driving machinery of various kinds, or for operating churns, pumps, and other similar apparatus, in which a reciprocating motion is required; and it consists of a double train of multiplying-gearing driven in opposite directions by means of weights, and imparting motion to a driving-shaft provided with a fly-wheel and a crank, which gives an oscillating motion to a rock shaft or lever, which imparts the proper reciprocating motion to the dasher-rod, piston-rod, &c., of the churn, pump, or other apparatus.

In the drawings, Figure 1 is a front elevation of my improvement, and Fig. 2 an end view of the same.

A represents a frame, of metal or other material, of suitable strength, and B B' the double train of multiplying-gearing, consisting of two sets of gear-wheels, each set consisting of three large wheels, b b b, and two small wheels, b' b', mounted on the shafts C C C and geared together, as shown, in the manner of ordinary clock-work. Between the upper wheels of the double train I arrange a driving-shaft, D, carrying a gear-wheel, H, and fly-wheel I. The front end of said shaft projects through the frame A, and is provided with a crank, K, as shown in Fig. 1. The crank-pin on said crank works loosely in a sliding block, L, which travels in a slot in the end of the oscillating lever M, which is secured to the frame A at one side by means of a pin, N, upon which it works. The other end of said lever carries an oscillating ring or socket, O, by means of which the piston-rod, dasher-rod, &c., may be attached to said lever, said ring being provided with a set-screw for the purpose. The lower shaft of each train carries a barrel or

drum, P, to which is attached a weight, Q, by means of a suitable cord, R, and the central shaft of each train, projects through the back of the frame A, and is squared, as shown, so that a key may be secured thereon for the purpose of winding. The said shaft, in each train, is attached loosely to the large wheel thereon, and is provided with the usual pawl and ratchet wheel for carrying the wheel forward, and allowing the weights to be wound without moving the whole train in the same manner as in ordinary clock-gearing. These ratchets are so arranged that the trains or sets will be wound in opposite directions, so that the proper motion will be given to the upper wheel in each set to drive the driving-shaft of the apparatus.

The operation of my apparatus will be readily understood.

Upon winding up my apparatus the lower wheels of the double trains will be put in motion, imparting motion in turn to the rest of the gearing. The upper wheels will travel much faster than the lower wheels, giving a rapid motion to the driving-shaft and oscillating lever without running the weights down too rapidly. The two sets of the double train working together double the power of the machine, as will be evident.

Having thus described my invention, what I claim as new, and desire to secure by Letters Patent, is—

The driving-shaft D, fly-wheel I, crank K, and wheel H, in combination with the sliding block L, slotted oscillating lever M, swinging ring or socket O, and double train of multiplying-gearing, all constructed and operating substantially as described, for the purpose specified.

In testimony that I claim the foregoing I have hereunto set my hand.

GEORGE I. SLATER.
